UNITED STATES PATENT OFFICE.

WILLIAM B. FLEMING, OF SOUTH PASADENA, CALIFORNIA.

SELF-PLAYER INSTRUMENT.

992,178.

Specification of Letters Patent. Patented May 16, 1911.

Application filed November 27, 1908. Serial No. 464,521.

To all whom it may concern:

Be it known that I, WILLIAM B. FLEMING, a citizen of the United States, residing in the city of South Pasadena, State of California, have invented certain new and useful Improvements in Self-Player Instruments, of which the following is a specification.

My invention relates to an improvement in self-player instruments, and it has for its object to provide means whereby the operating parts of the instrument may be controlled so as to regulate the force with which the hammer strikes the strings of a piano or similar instrument and whereby the tones produced may be modified and modulated so as to more nearly reproduce and represent the tones which may be produced by a skilled performer upon a piano or similar instrument.

20 A convenient embodiment of my invention is illustrated in the accompanying drawings forming a part of this specification. The novel features of this and all other embodiments which come within the scope of my invention I have endeavored to point out with particularity in the appended claims.

In the drawings:—Figure 1 is a transverse vertical section of a self-player piano, provided with my invention; Fig. 2 is a longitudinal section of a pneumatic regulator device, including portions of air tubes connected to the regulator; Fig. 3 is a plan view of the pneumatic regulator shown in Fig. 2; Fig. 4 is a transverse section of the pneumatic regulator, certain parts thereof occupying a different position relatively to each other from what is shown in Fig. 2; and Fig. 5 is a transverse section of a modified construction of adjustable controlling mechanism shown in Fig. 1.

40 Referring to the drawings:—1 designates the framework of the instrument; 2 designates a key; 3 designates a hammer; 4 designates a jack; and 5 designates a damper, all of the said parts being of usual construction.

10 designates valve mechanism communicating through tubes, one of which is shown at 11 in Fig. 1, with a tracker board (not shown).

50 12 designates one of a number of power pneumatics which, together with the valve mechanism 10, is of any known construction.

55 The hammers are operated by means of their respective jacks, one of which only is shown in the drawings. It will be under-

stood that the usual number of hammers, jacks, and the operating parts connected thereto are employed. Only one train or set of these parts is shown in the drawings, as it is not necessary to my invention to show all the parts of a self-player piano. The description of the same in connection with one train or one set of hammers, jacks, keys, and their connections, is descriptive of all the rest and by thus confining the drawings the showing of the invention is simplified. The jack 4 is pivotally connected to a pivoted lever 15 which is adapted to be operated when the piano or similar instrument is being mechanically played by means of a rod 16 which is controlled and operated by means of the power pneumatic 12. The movement of the lower side of the pneumatic 12 which is connected to the rod 16 occasions movement of the latter and its upper end strikes the lower side of an adjustable stop 17 secured upon the inner end of the lever 15. It will be understood also that the lever 15 may be operated by the keys 2 through the action of a rod or bar 20, the lower end of which is located in contact with a member or portion 21 carried by the inner end of the key. It is obvious that the raising of the inner end of the key occasions an upward movement of the part 20 to operate the lever 15 and its connected jack 4.

It is desirable to control and to limit the upward movement of the rod 20 and the parts connected thereto, including the jack 4, so as to control the striking force of the hammer 3, and this is accomplished by me in the following manner:—I provide a stop bar 30 hinged at 31 upon the frame of the instrument which bar is connected to the upper end of a rod 32, the lower end of which is connected to one arm 33 of a bell crank lever, the other arm 34 of which is connected to a rod 35, which extends to the front of the instrument and is adapted to be moved in and out to raise and lower the rod 32 which occasions the raising and lowering of the bar 30. To connect the rod 32 to the bar 30, I provide a short rod 36 which is fitted pivotally in a seat as indicated in the bar 30, and is held in place by means of a plate 37 which extends thereover as shown in Fig. 1. The inner edge of the pivoted bar 30 is provided with a felt or other suitable contact 40, with which the upper side of a member 41 is adapted to contact and which is adjustably secured to the rod 20. It will

be seen that the position of the inner edge of the bar may be adjusted to different heights and locations by means of the rods 32-35 and the bell crank lever intermediate the said rods and that therefore the upward movement of the rod 20 may be limited and varied as desired, thus limiting and varying the upward movement of the lever 15 under the influence of the power pneumatic 12.

- 10 Coöperating with the mechanism just described, I have provided an additional means for controlling the loudness or volume of the sounds produced upon a self-playing piano or similar instrument, which means is illustrated in Figs. 2, 3 and 4, and consists of a pneumatic regulator consisting of the opposite members 50 and 51 hinged together at 52. The edges of the members 50 and 51 are connected by means of flexible material which 20 permits of relative movement between the said members. The member 51 is provided with valves 53 which are adapted to close ports or openings 54 in the member 50. In order to hold the valves downwardly in the 25 position indicated in Figs. 2 and 4, I have provided rods 55 which extend through the member 51 and also through the valves 53 and have coiled about the said rods springs 56 which are located between the lower side of 30 the member 51 and the valves 53 and are adapted to hold the valves downwardly as indicated in the said Figs. 2 and 3, but are also adapted to permit a vertical movement of the valves upon the rods 55 by the compression and expansion of the springs. Upon 35 reference to Fig. 3 it will be noted that two of these valves are provided. This is for the purpose of insuring a free outlet for the air which enters the regulator. The air is 40 drawn by suction out of the regulator, that is out of the space between the members 50 and 51, through a tube or pipe 60 by means of a bellows (not shown) of any known construction.
- 45 61 designates a tube or pipe which is connected to the valve mechanism 10 in the usual manner (the connection not being shown). It will be understood that the air passes from the valve mechanism 10 through 50 the tube 61 to the regulator in a manner well known.
- 55 In order to regulate the force or power necessary to lower or carry the member 51 from the position shown in Fig. 4 to that shown in Fig. 2, I have provided a rod or bar 65 which is located above and parallel to the upper side of the member 51, and is connected to the latter by means of a rod 66 and a bracket 67.
- 60 65 70 designates a grooved wheel which rides underneath the bar 65, which wheel is connected to a rod 71, which extends to and is supported upon a spring 72. The lifting or supporting effect of the spring 72 through 65 the rod 71 upon the member 51 of the regu-

lator varies with the position of the wheel 70 upon the bar 65. When the wheel 70 is in the position indicated at the right in dotted lines in Fig. 2, it will be understood that the lifting or supporting effect is relatively 70 small, due to the nearness of the said wheel to the pivot 52 of the member 51. As the wheel 70 is moved to the left from the said dotted line position, it will be understood that its lifting and supporting effect or 75 power increases according to a well known law in mechanics so that when it reaches the dotted line position indicated at the left of Fig. 1 of the drawings, the lifting or supporting effect or power of the said spring is relatively great. By thus varying the position of the said wheel, I vary the force necessary to carry the member 51 to its lowermost position indicated in Fig. 2 of the drawings. As a result a larger quantity and volume of air 80 is necessary to be removed from and through the space between the members 50 and 51 to permit the closing down of the member 51 when the wheel is in the left hand dotted position than when it is in the right hand 85 position, and it will be understood that such force varies an infinite number of times, depending upon the infinite number of positions to which the wheel 70 may be moved along the bar 65. By thus 90 varying the quantity and volume of air, the action of the power pneumatic 12 is affected, being accelerated and occasioning an increase in the force of the blow of the hammer when and as the quantity and volume of air 95 passing through the regulator is increased and retarding or decreasing the speed of the action or operation of the pneumatic and diminishing the force of the blow of the hammer when and as the quantity and volume 100 of air passing through the regulator is decreased.

For the purpose of shifting the wheel 70, I provide the rod 73 which extends to the front of the instrument, and by means of 110 which the said wheel may be moved back and forth upon the rod 65.

By combining the pneumatic regulator with the mechanism previously described for controlling the throw of the jack and 115 the hammer, I am enabled to control and operate the parts so as to secure the pleasing effect of the human touch and execution.

In Fig. 5 I have shown a modified construction of the connection between the rod 120 or bar 32 and the stop bar 30. In the construction shown in this figure, I have provided a recess or cut out portion 80 and have connected a spring 81 to the bar 30 which spring extends over the said recess or cut out 125 portion and engages loosely with the shank or body portion of a screw 82. The rod 32 is connected to the bar 30 by means of a screw 83. The portion of the spring beyond the screw 82 is adapted to contact with the 130

adjustable stop 41, adjustably secured to the member 20. The contacting of the adjustable stop 41 with the spring occasions upward movement of the latter to bring it into contact with the buffer or pad 84 of felt or similar material. By the interposition of the spring 81 with which the adjustable stop 41 comes into contact when it is moved upwardly, I decrease the shock incident to the striking of the adjustable stop 41 directly against the buffer or pad 40 shown in Fig. 1 or with the buffer or pad 84 shown in Fig. 5.

Having thus explained the nature of my invention, and described a way of constructing and using the same without attempting to set forth all of the forms in which it may be made, or all of the modes of its use, what I claim is:—

20 1. In a self-player instrument, the combination of the hammer actuating mechanism, a regulator, means operatively connecting the said hammer actuating mechanism and the said regulator, the said regulator including a chamber having air inlet and outlet passages, means for closing one of said passages and means for varying the force necessary to close the said passage whereby the speed and striking force of the 25 hammer actuating mechanism may be varied, the said last mentioned means comprising a spring, a connection between the said spring and a movable part of the said regulator and means for varying the point 30 of connection between the said spring and the said part.

2. In a self-player piano, the combination of a power pneumatic means for limiting the extent of movement of said power pneumatic, hammer actuating mechanism connected with the said pneumatic, a regulator communicating with the said power pneumatic to control the rapidity of its action, and means for adjusting the said regulator 45 for the purpose of varying the volume of air which passes through it and thereby adjusting the speed or rapidity of action of the said pneumatic, the said last mentioned means comprising a swinging spring supported member having connection with a movable part of said regulator, and means for varying the position of said spring-supported member with respect to said movable part.

3. In a self-player piano, the combination of a power pneumatic, hammer actuating mechanism connected to the said pneumatic means for limiting the extent of movement of the said pneumatic and the said hammer actuating mechanism, and means for regulating and controlling the rapidity of movement of the said pneumatic, and the said actuating mechanism, the said last mentioned means comprising a pneumatically 60 operated device, a spring, a connection be-

tween the said spring and a movable part of the said device, and means for varying the point of connection between the said spring and the said movable part.

4. In a self-player piano, the combination 70 of hammer actuating mechanism, a power pneumatic, means for regulating and controlling the rapidity of movement or action of the said pneumatic, the said means comprising an air controlled device having 75 a movable member, a spring, means for connecting said spring to the said movable member, and means for adjusting the point of connection between the said connecting means and the said movable member 80 for the purpose set forth.

5. In a self-player piano, the combination 85 of a power pneumatic, means for controlling the speed of movement of the said pneumatic, the said means comprising a hinged member, and adjustable means connected to the said hinged member, the point 90 of connection between the said hinged member and the said adjustable means being movable toward and from the position of the hinge so as to decrease and increase the power of the said regulator, and means operatively connected to said pneumatic and actuated thereby to occasion musical sounds.

6. In a self-player piano, the combination 95 of hammer actuating mechanism, a power pneumatic co-acting with said mechanism, means for limiting the extent of movement of the said pneumatic, means for regulating and controlling the speed of movement of 100 the said power pneumatic, the said regulating means comprising a member movable about a pivot, means for exerting a variable supporting or holding force upon the said movable member, and means for adjusting the said last mentioned means toward and from the said pivot so as to decrease and increase the power of the said regulating means.

7. In a self-player instrument, the combination of hammer actuating mechanism, a power pneumatic associated with the said hammer actuating mechanism and having a part adapted to actuate the said hammer mechanism, a regulator for controlling the speed of movement of the said power pneumatic, the said regulator comprising a collapsible chamber having movable and stationary sides, the said movable side having pivotal connection at one edge to the said stationary side and the said chamber having air inlet and outlet passage ways, and the said movable side supporting a valve which is adapted to close one of the said passage ways when the said movable side is moved toward the stationary side, an adjustable spring supported device for exerting a lifting force upon the said movable side, and means for moving the said device toward and from the hinged edge of the said mov- 110 115 120 125 130

able side whereby the force necessary to occasion movement of the said movable side toward the stationary side may be varied.

8. In a self-player instrument, the combination of a regulator comprising a pivoted member, power pneumatics, a movable device for regulating the action of said regulator and thereby increasing or decreasing the wind pressure on the said pneumatics, the 10 said movable device having operative connection with said pivoted member, spring-supporting means for supporting the said movable device, and means for moving the said movable device toward and from the 15 pivot of said pivoted member to vary the leverage of the said spring-supporting means with respect to the pivot of said pivoted member and thereby control the action of said regulator.
9. In a self-player instrument, the combination of a power pneumatic and means operatively connected to said pneumatic and actuated thereby to cause musical sounds with a regulator, means for controlling the 20 action of said regulator, the said means comprising a movable wheel having operative connection with the said regulator, a spring, and a flexible connection between the 25 said wheel and the said spring.
10. In self-player instruments, the combination of hammer actuating mechanism, power pneumatics having connection with the said hammer actuating mechanism to 30

actuate the same, and means for controlling the wind pressure in said pneumatics, such means comprising a chamber, air inlet and outlet passage ways communicating with said chamber, a valve for closing one of said passage ways which valve is supported upon a pivotally movable member, a spring supported device having connection with said pivotal member, and means for moving said device toward and from the pivotal point of said pivotally movable member whereby the force or pressure necessary to close said valve 45 is varied to thereby vary the wind pressure in the said pneumatics.

11. In a self-player instrument the combination of a power pneumatic and means operatively connected to said pneumatic and 50 actuated thereby to cause musical sounds with a regulator comprising a pivoted member, means for controlling the action of said regulator, the said means comprising a wheel having connection with said pivoted member, and means for causing movement of said wheel toward and from the pivot of said pivoted member.

In testimony that I claim the foregoing as my invention, I have hereunto signed my 60 name this 24th day of November, A. D. 1908.

WILLIAM B. FLEMING.

In the presence of—

CYRUS N. ANDERSON,
S. SALOME BROOKE.
